(57) **CLAIM**

I claim the ornamental design for a sewer hose kit, as shown and described.

DESCRIPTION

FIG. 1 is a perspective view of a sewer hose kit showing my new design;

FIG. 2 is an exploded perspective view thereof;

FIG. 3 is a front view thereof;

FIG. 4 is a back view thereof;

FIG. 5 is a right-side view thereof;

FIG. 6 is a left-side thereof;

FIG. 7 is a top view thereof; and,

FIG. 8 is a bottom view thereof.
